UNITED STATES PATENT OFFICE

CHARLES R. THORBURN, OF CINCINNATI, OHIO, ASSIGNOR TO THE A. S. BOYLE COMPANY, OF CINCINNATI, OHIO, A CORPORATION OF OHIO

FLOOR POLISHER

Application filed November 4, 1929. Serial No. 404,780.

The invention relates to floor polishers or the like and has as an object the provision of a polisher adapted to be used with an extended handle upon floors.

It is an object of the invention to provide a device of this character having novel means to clamp polishing material upon the supporting member.

It is a further object of the invention to provide a novel form of structure for such supporting member.

It is a further object of the invention to provide a novel construction of clamping means for the polishing material.

Further objects of the invention will appear from the following description when read in connection with the accompanying drawings showing an illustrative embodiment of the invention and wherein:—

Fig. 1 is a plan view;

Fig. 2 is a vertical transverse section on line 2—2 of Fig. 1;

Fig. 3 is a like section showing the clamps disengaged;

Figs. 4 and 5 are perspective views respectively of portions of the apparatus; and

Fig. 6 is a plan view of a modified form.

As shown the device comprises a supporting member 10 of plate-like form having edges 11, 12 integral therewith and turned upwardly from the plane thereof, and handle and clamp attaching lugs 13, 14, 15, 16 struck from the material of said plate 10 and projecting upwardly therefrom as shown.

To attach a handle and polishing material clamping means to said plate 10, there is shown a rod 17 passing through apertures in said members 13—16 and secured therein as by having the ends of the rod upset exterior

of lugs 13 and 14. A handle 18 is shown attached to the rod 17 by means of a socket 19 in which the handle is inserted and formed of a single piece of material, one portion of which is formed into the socket 19 and a second portion of which is formed into a loop 20 enclosing the rod 17, the loop 20 being of sufficient lateral extent to be received between the lugs 15, 16 thereby pivotally attaching the handle to the rod 17.

To attach polishing material as sheepskin

21 to the supporting plate 10, there are shown a pair of lateral clamping members 22, 23. Each of said members 22, 23 is formed from a single piece of material deformed to present a bar-like member 24 formed with a bead or ridge 25 to stiffen the same, the ends of the member 24 being turned to provide members 26, 27 to engage the rod 17 and one edge of the bar 24 being turned to provide a member 28 at an angle to overlap the upper edges of members 26, 27 as at 29, 30.

To cause the members 22, 23 to clamp the polishing material 21 against the upper surface of the plate 10, each of said portions 26, 27 of the members is provided with a cam slot 31, 32 through which the rod 17 passes. When the members 23, 24 are pulled outwardly the ends of the portions 26, 27 will ride upwardly upon the rod 17 until the rod lies in the extremity of the slot when the members 23, 24 may be swung upwardly about the rod 17, as indicated in Fig. 3. The sheet of material 21 may then be placed under the plate 10 and have its ends bent over the edges 11 and 12 whereupon the members 22, 23 may be brought down into contact with the sheet of material and then forced inwardly to the position shown in Fig. 2 in which position the lower outer corners of members 26, 27 will press against the plate 10 or the sheet of material 21 and due to the form of the cam slots 31, 32 the bar 24 will be forced down against the edges of the sheet of material to firmly clamp the same upon the plate 10.

When assembled in the manner indicated, liquid wax or the like may be applied to the polishing material and applied to the floor in the well understood manner.

The portions 26, 27 are shown as engaging a single rod 17 in overlapping relation, for purpose of illustration. If greater lateral extent of the supporting plate 10 is desired it will be obvious that two parallel bars may be provided on the plate, each bar coacting with one only of the clamps, in which case the handle member 19, 20 may engage either of said rods corresponding to rod 17 or the handle may be pivoted upon a third rod supported intermediate said parallel rods, at

the center of the plate, in which case the rods 17 may be mere pins at each end of the plate.

While an illustrative embodiment of the invention has been described as a polishing pad, it is apparent that the invention may 5 be utilized as a sandpaper block, a blotting paper pad, a manicure pad, or for any service where it is desired to clamp a sheet of material upon a carrying plate.

10 Minor changes may be made in the physical embodiment of the invention within the scope of the appended claims without departing from the spirit of the invention

I claim:

15 1. A polishing device or the like comprising, in combination, a sheet supporting plate, a cam engaging means secured to said plate, a clamp bar and cam means carried by said bar coacting between said bar and engaging 20 means to actuate said bar to clamp a sheet of material upon said plate.

25 2. A polishing device or the like comprising, in combination, a sheet supporting plate, a member carried by said plate in spaced relation to one surface thereof, a clamp bar having a portion projecting laterally therefrom, said portion having a cam slot slidably engaging said member, said slot extending obliquely away from said plate toward said 30 clamp bar when said bar is in clamping position.

35 3. A polishing device or the like comprising, in combination, a sheet supporting plate, a rod fixedly supported on said plate in spaced relation to one surface thereof, a pair of clamp bars each having a member extending from each end thereof, said members each provided with cam means coacting with said rod, the cam carrying portions of the respective members engaging the rod in overlapping relation, said cam means forcing the bars toward the plate when the bars are moved laterally toward the rod.

40 4. A polishing device or the like comprising, in combination, a sheet supporting plate, a perforated ear bent from the material of the plate at each end thereof, a rod supported in said perforations in spaced parallel relation to a surface of said plate, a clamp bar, 45 the ends of said bar bent perpendicular thereto to provide arms, cam means carried by each arm coacting with said rod to press the bar toward the plate when the bar and arms are moved toward the rod.

55 5. A polishing device or the like comprising, in combination, a supporting plate the edges thereof turned to a position perpendicular thereto, a perforated ear formed on said plate at each end thereof standing perpendicular thereto, perforated ears integral with said plate intermediate the length thereof, said perforations being in alignment with the perforations in said first named ears, a rod supported in said perforations, clamping bars 60 each having an arm at each end thereof, cam 65

means carried by said arms coacting with said rod in overlapping relation with the cam means upon the opposite bar coacting with said rod to force said bars toward the surface of the plate to clamp a sheet thereon when the bars are forced toward the rod and a handle-carrying member pivoted upon said rod between said intermediate ears.
